UNITED STATES PATENT OFFICE.

EDWIN F. HULBERT, OF SOUTH NORWALK, CONNECTICUT.

COMBINED HINGE AND HANDLE.

966,020.

Specification of Letters Patent. Patented Aug. 2, 1910.

Application filed December 29, 1909. Serial No. 535,443.

To all whom it may concern:

Be it known that I, EDWIN F. HULBERT, citizen of the United States, residing at South Norwalk, in the county of Fairfield 5 and State of Connecticut, have invented certain new and useful Improvements in Combined Hinges and Handles, of which the following is a specification.

This invention comprehends certain new 10 and useful improvements in receptacles or display cases that are provided with swinging lids or closures so arranged that they are turned aside in order to obtain access to the contents of the case, and relates partic- 15 ularly to a novel construction and arrangement of the hinge connection between the body portion of the receptacle or display case and the lid thereof, the present invention being designed especially for embodiment 20 in display cases for containing oysters in bulk, for use by a dealer in serving his customers, although it is to be understood that the invention is applicable for other uses generally.

25 The primary object of my invention is a hinge which will effectually protect the lid or cover from becoming broken by being accidentally dropped against the rim of the opening which it is designed to close, provision being made whereby the lid must be raised first before swinging it to one side or the other, and must be brought back to a position directly over the opening before it can be again dropped, a gasket being prefer- 30 ably provided around the margin of the opening, and the lid being adapted to rest in its closed position on the gasket, the lid being preferably constructed of plate glass to add to the attractiveness of the case or re- 35 ceptacle.

40 The invention also has for its object, an improved construction of hinge of this character the parts of which are capable of being easily manufactured and readily assembled 45 and which will be attractive in appearance as well as durable and which will embody in the one structure a combination of hinge proper and handle, the handle forming a component part of the hinge and serving as 50 a brace therefor in addition to its function as a hand grip.

With these and other objects in view as will more fully appear as the description proceeds, the invention consists in certain 55 constructions, arrangements and combina-

tions of the parts that I shall hereinafter fully describe and claim.

For a full understanding of the invention, reference is to be had to the following description and accompanying drawings in 60 which:

Figure 1 is a perspective view of a receptacle embodying the improvements of my invention: Fig. 2 is a top plan view thereof, a portion of the lid being broken away; 65 and, Fig. 3 is an enlarged sectional view of the upper portion of the receptacle, the hinge being shown partly in side elevation and partly in section.

Corresponding and like parts are referred 70 to in the following description and indicated in all the views of the accompanying drawings by the same reference characters.

In the present embodiment of my invention, referring now to the drawing, the num- 75 eral 1 designates the top of a case for oysters or other commodities, the same being provided with a preferably centrally dis- posed opening 2 by which access may be had to the contents of the case, the said opening 80 being defined by a depressed rim 3 prefer- ably formed in its upper face with an annular groove 4 to receive a ring or gasket 5, the groove being preferably spaced from the main portion of the top as clearly illustrated 85 in the drawing.

6 designates the lid of the case, said lid being preferably circular and formed of plate glass which will add to the attractiveness of the case, as well as to the hygienic condition 90 thereof as it may be easily kept clean. The lid 6 is secured by screws or similar fastening devices to a hinge member 7, which is preferably formed integral at one end with a vertically disposed sleeve 8. The hinge 95 member 7 extends perpendicularly from the sleeve 8 in a plane at right angles to the axis of the sleeve, and said sleeve is adapted to move vertically as well as turn laterally upon a post 9 which rises from the top 1. 100 The vertical post may be secured to the top in any desired way as, for instance, by being slipped through an opening formed in the top so as to rest upon an annular flange 10, the post being threaded below the flange and 105 slipped through a block 11 located at the underside of the top 1, a lock nut 12 screwing on the lower extremity of the post to secure the same in place. A cap 13 is 110 screwed or otherwise secured on the upper

end of the post 9, so as to prevent the accidental detachment of the hinge member 7 and to limit the up and down movement thereof. The post 9 is formed with a laterally extending pin or projection 14, and the sleeve 8 is formed in its lower edge with an upwardly extending recess 15 which in the present instance is of such a depth that when the sleeve is at the lower limit of its movement with the pin at the upper end of the recess, the lower edge of the sleeve will be clear of the base or annular flange 10 of the post and the hinge member 7 will be held in a relatively suspended position on the post.

15 It is to be particularly noted that the pin 14 and recess 15 are so positioned relative to the lid and the leaf of the hinge member 7 that the pin will register with the recess only when the lid 6 is directly over the opening 2 and the gasket 5 surrounding the same. Hence, only at this position can the lid be lowered, and in order to raise the lid, it is necessary to slip the sleeve 8 upwardly on the post 9 so as to disengage the pin 14 20 from the recess 15 whereupon the hinge member with the lid attached to it can be easily turned to one side or the other, the lower edge of the sleeve 8 resting upon the pin. Preferably there is some slight play in 25 the upward movement of the hinge member, that is, the sleeve is not quite as high as the distance between the pin 14 and cap 13, so that the recess may be easily slipped away from the pin in the upward movement of the 30 hinge member and lid.

In order to provide a hand-grip for the lid, and at the same time, a brace for the hinge member, the latter is connected to the sleeve by a bar 16 which extends from a 35 point near the outer extremity of the lid attaching leaf of the hinge member to the sleeve at the upper end of the latter, being connected only at its end to those parts whereby an opening below it will be formed 40 through which the operator's fingers may easily pass.

From the foregoing description in connection with the accompanying drawings, the 45 operation of my improved hinge will be apparent.

In the practical use of the device, it being presumed that the lid is down upon the gasket 5, in order to move the lid to an open position away from the opening 2, it is 50 only necessary to grasp the brace bar 16 as a handle and to raise the lid upwardly so as to disengage the pin 14 from the recess 15 whereupon the lid may be easily swung around either to the right or to the left to 55 an open position with the lower edge of the sleeve resting upon the pin while the case or receptacle receives its contents, or while the same are being removed. As it is impossible

to lower the lid except when it is directly over the opening 2 and the gasket 5 which surrounds the opening, it is obvious that the lid can not be dropped upon the top 1, but can only be lowered when it is directly over the opening 2. Hence all liability of shattering or otherwise injuring the lid by accidentally dropping it upon the top 1 which is preferably constructed of sheet metal, is effectually precluded.

Having thus described the invention, what is claimed as new is:

1. A hinge comprising a hinge post, a hinge member, a sleeve connected to one end of the hinge member, the hinge member projecting perpendicularly from the sleeve and lying in a plane at right angles to the axis of the sleeve, the sleeve being mounted to turn and slide longitudinally on said post, a brace bar connected to the hinge member near the outer end thereof, and also connected to the sleeve above the point of connection of the sleeve with the hinge member and providing below the bar, an opening for the insertion of one's fingers, whereby the bar will serve not only as a brace, but as a handle.

2. As a new article of manufacture, a hinge comprising a hinge post provided with an annular base flange, said post being provided above said flange with a projection and at its upper end with a detachable cap, 95 a sleeve adapted to be slipped over the post upon the removal of the cap and mounted for a turning and a longitudinally sliding movement thereon, the sleeve being provided with a recess in its lower edge adapted to 100 accommodate said projection and a hinge member secured to and projecting perpendicularly from the sleeve, for the purpose specified.

3. As a new article of manufacture, a 105 hinge comprising a hinge post provided with an annular base flange and a threaded portion at one side of the flange, the post being provided at the other side of said flange with a pin and at its end adjacent said pin with a detachable cap, a hinge member provided with a sleeve adapted to be slipped over the last named end of the post and mounted for a turning and a longitudinally sliding movement thereon, the sleeve being 110 provided with a recess adapted to accommodate said pin, and a web connecting the hinge member to the sleeve as and for the purpose specified.

In testimony whereof I affix my signature 115 in presence of two witnesses.

EDWIN F. HULBERT. [L. S.]
